CHARLES HINKLEY, OF WILLIAMSVILLE, NEW YORK.

Letters Patent No. 66,024, dated June 25, 1867.

IMPROVED LIME-KILNS.

The Schedule referred to in these Letters Patent and making part of the same.

TO ALL WHOM IT MAY CONCERN:

Be it known that I, CHARLES HINKLEY, of Williamsville, in the county of Erie, and State of New York, have invented certain new and useful improvements in Lime-Kilns; and I do hereby declare that the following is a full and exact description thereof, reference being had to the accompanying drawings making part of this specification, in which—

Figure 1 is a vertical longitudinal section in the plane of line $y y$, fig. 3.

Figure 2 is a vertical transverse section in the plane of line $z z$, fig. 3.

Figure 3 is a horizontal section in the plane of line $x x$, fig. 1.

Similar letters of reference indicate like parts in all the figures.

This invention relates to new and useful improvements, in perpetual lime-kilns or calcining furnaces, whereby the charge is more evenly burned than heretofore, and whereby a more free and perfect combustion of the fuel is obtained, and the firing performed with greater facility than heretofore, as hereinafter explained.

The invention consists in giving the body of the cupola such form that its burning-chamber is, in horizontal section, of an elliptical form, and employing in connection therewith two fire-places or furnaces, which are located on opposite sides of the cupola, and in line of its shorter diameter, these furnaces having arched or crowning roofs, and flaring considerably upward and laterally toward the charge-chamber, the furnaces so constructed thereby delivering to the centre of the charge a greater proportion of heat, relatively, than by the ordinary construction of furnaces and cupola. The invention also consists in providing each fire-place with an elevated flue, which communicates with the top of the fire-place near its door, and passing over the fire-place connects with the cupola-chamber at a point more or less above the main connection of the fire-place with said chamber; by which arrangement air is supplied to the rear sides of the fires, for a more perfect combustion of the gases and smoke, and outward flow of smoke and flame is prevented when the furnace doors are opened for firing. And the invention further consists in an improved construction of the piers or pillars, at the intersection of the fire-places with the cupola-chamber; these pillars being, in cross-section, of a triangular or V form, with the base toward the cupola-chamber, thereby presenting a flat face for the charge to rest against, while a sharp front is presented toward the fire, so as to offer but little obstruction thereto, and also to allow the poker to be inserted and used more freely when punching down clinkers, &c.

A, in the accompanying drawings, is the cupola or charge-chamber; B B are the furnaces or fire-places; C C are the ash-pits; d d d are the fire-grates; h h are V piers or pillars; g is the draw-passage; e e are air-flues, and f f are dampers for regulating the capacity of the same.

It is a fact well known to experienced lime-manufacturers that the centre of the charge is the last to burn, and that it is a matter of considerable difficulty to burn the charge with that degree of uniformity which is desirable. To overcome this difficulty I construct the cupola and furnaces as follows: The cupola A, fig. 3, is made in an elliptical form, and the furnaces B B are placed on opposite sides of it in line of its transverse axis, so that the partition walls, formed by the triangular pillars, conform to the elliptical sides of the cupola, partially surrounding the same. Each furnace is constructed with its top or roof and sides gradually diverging or receding from each other, and the bottom, from the outer opening to their intersection with the cupola, with the roof arched or made crowning, as shown at z , fig. 2.

This gradual enlargement of the furnace from the outside possesses the following advantages over those which are simply enlarged at their inner end a part of their length, viz, first, it enables the cupola and contents to be more readily inspected, as there is no angle or sudden bend to obstruct the view, as is the case when the walls are parallel a part of the way, and then suddenly enlarge; and, secondly, the furnace can be more readily supplied with fuel, the combustion of the same is more perfect and rapid, as the draught of the flame inward is more direct, less conflicting and obstructed, and the poker can be used more conveniently when required.

The curved form of the division wall h h, in connection with the peculiar form of the cupola, unpartitioned, having a furnace on each side, produces a concentration and tendency of the heat to the centre of the charge, which is so essential to the perfect burning at that point, to a degree unequalled by any other furnace with which I am acquainted. In addition to this the arched or crowning roof gives more ample space at the centre

for the flame, which also increases the heat at that point. The draw-passage *g* I prefer to close by folding doors, which, when opened, leave an aperture the full size of the passage and bottom of the kiln that enables the charge to be more readily withdrawn than when the mouth of the flue is divided by a central upright plate or pillar, as is ordinarily the case.

Each furnace is provided with a draught and air-flue, *e*, passing from the roof near the outer end, over the former, and opening into the cupola at a point above the intersection of the furnace as represented. These flues may each be provided with a suitable damper, *f*, fig. 1, operated from the outside, by which their capacity can be regulated, which dampers are always fully opened before the opening of the furnace doors, which permits a free passage of the smoke and flame through the same that would otherwise flow outward through the open aperture. The employment of these auxiliary flues not only prevents the efflux of the smoke and flame when the furnace doors are opened, as just described, but also prevents that excessive heating of the doors which frequently occurs, and especially with a strong and adverse wind. By supplying air to the flame on each side of the cupola at their intersection therewith, secures a more perfect combustion of the gases and other volatile products which would otherwise pass off unconsumed, and be thereby wasted. The piers or pillars *h h* are made in a V form, as shown in fig. 3, and placed so as to present a square face toward the cupola, and a sharp front toward the fires. By this construction they offer but little obstruction to the passage of the flames, as there is no flat surface for them to directly impinge against, as is the case where the pillars are of the usual square or rectangular form. They also allow the lime or other charge of the cupola to be more readily inspected; and when it is necessary to use the poker for punching down clinkers, they are less in the way than when constructed in the ordinary manner. This furnace may also be used for calcining gypsum, of which there are extensive deposits in some of the newer portions of the country.

Having thus described my invention, what I claim as my invention, and desire to secure by Letters Patent, is—

The combination and arrangement of the elliptic cupola *A*, the inwardly widened furnaces *B B*, sharp-edged pillars *h h*, and flues *e e*, as and for the purposes herein specified.

In witness whereof I have hereunto signed my name in the presence of two subscribing witnesses.

CHARLES HINKLEY.
